UNITED STATES PATENT OFFICE.

HINSDALE SMITH, OF SPRINGFIELD, MASSACHUSETTS.

SEAT-CONNECTING APPLIANCE FOR VEHICLES.

SPECIFICATION forming part of Letters Patent No. 781,565, dated January 31, 1905.

Application filed May 17, 1904. Serial No. 208,416.

To all whom it may concern:

Be it known that I, HINSDALE SMITH, a citizen of the United States of America, and a resident of Springfield, in the county of Hampden 5 and State of Massachusetts, have invented certain new and useful Improvements in Seat-Connecting Appliances for Vehicles, of which the following is a full, clear, and exact description.

This invention relates to improvements in vehicle-bodies and seats connected thereon, and more particularly pertains to constructions for attaching double rounded seats together and to the body, so that the seats may 15 be readily fastened in place or removed, as occasion may render desirable; the invention in part having reference to the formation of the attaching devices, whereby the fastenings are concealed and whereby at the adjoining 20 forwardly-extended portions of both seats a smooth and continuous edge for the forward extensions of the rounded backs are provided.

The invention consists in the combination or arrangement of parts and the construction 25 of certain of the parts, all substantially as hereinafter fully described, and set forth in the claims.

The improvements are illustrated in the accompanying drawings, in which—
30 Figure 1 is a plan view showing double individual seats side by side connected together and to the vehicle-body. Fig. 2 is an elevation with parts in section as taken on the line 2 2, Fig. 1. Fig. 3 is a partial sectional view 35 through the sidewise adjacent forward extensions of the backs of the two seats and the connection-piece therefor, the line 3 3 indicating the section. Fig. 4 is a perspective view of the connection-piece for the two side- 40 wise adjoining seats. Fig. 5 is a perspective view of one of the individual seats. Fig. 6 is a perspective and partial sectional view illustrating the form of connection at the rear for one of the seats with a part of the body.

45 Similar characters of reference indicate corresponding parts in all of the views.

In the drawings, A represents the main or under body of a vehicle, the same having at a forward portion thereof the parallel separated 50 transverse girder-arches B B, which, as shown,

comprise angle-bars 9 9, having members thereof horizontal, and the upper edges of these girder-arches, constituted by the horizontal members of the angle-bars, serve as supports for the sidewise-arranged pair of individual seats C C, said seats (or seat-frames, as they may be more properly regarded) comprising seat-bottom boards a a and rounded sheet-metal backs b, having the opposite side extensions b², and surrounding the base of the 60 connected bottom and back are angle-bars e, suitably curved to conform to the plan contour of each seat, while at the upper edges of the seat-back and side extensions a continuous suitably-curved angle-bar c is provided, 65 the same being fastened by riveting, as indicated at 8, and having one angular member of this reinforcing-bar horizontal.

As indicated in Figs. 1, 2, and 5, the upper marginal reinforcing angle-bar for each of the 70 seat-backs and sides at the inner side of the seat is terminated, as indicated at 20, above and somewhat to the rear of the forward corner of the upright seat-side b², and as represented in Fig. 1, the flat and horizontal members of the angle-bars C C merge together 75 somewhat above and to the rear of their point of termination 20, so that these adjoined portions constitute parts of a continuous armrest for the seats. The arm-rest and further 80 continuation of the merged-together portions of the angle-bars c c for a flush-front formation and connection is constituted by the peculiarly-shaped metallic piece or casting G, which has a width equal to the combined width 85 of both angle-bars c c and a curvature corresponding to the front edge contour of both forward extensions b² of the two seat-backs, and at the lower forward end this connection piece has the transverse horizontal bar 7 projecting 90 from both sides of the median curved part 11, provided with inwardly-extending horizontal lugs 17, and the upper extremity of the casting G is formed with a rabbeted seat, as indicated at 95 15, to fit and underlap in relation to the horizontal portions of the angle-bars c c adjacent their point of termination 20, as aforesaid. The said connection piece or casting G furthermore has a plurality of lugs 12 12, extending 100 from its inner side, all located in the com-

mon vertical median plane of the structure, cross-perforations 18 being provided through these lugs, as shown in Fig. 4. The thickness of the lugs 12 is the same as the slight distance between the seat-back extenions b^2 b^3 , and bolts 19 are passed transversely and horizontally through the seat portions b^2 b^3 and the intermediate perforated lugs 12 12 of the connection-piece G.

- 10. The cross member 7 at the lower front is let into the front edge of both seat-boards, the angular and horizontally-extending lugs 17 17 underlying the seat-boards and resting on the horizontal member of the top angle-bar 9 of the front girder-arch B, and connection is here made by bolts 14 vertically applied, the same extending through perforations 14^a in the lugs 17 and through the horizontal member of the angle-bar 9, fastening-nuts being applied next under and in binding relation against the angle-bar.

The arrangement and combination of parts described not only impart an attractive and sightly appearance at adjoined portions of the two seats, and one which when finished is flush and continuous, but provide an effective means of fastening the adjoined front portions of the two seats together and onto the body in such a way that the fastenings are entirely concealed from view.

- 25. Further fastening means for holding the seats C C firmly on the body and against displacement consist, in part, of the bolts j j , which screw down through the seat-bottoms 35 and into the rearward girder-arch and in part of the devices represented at f and g in Figs. 1, 2, and 6, the part f being a lug riveted on an elevated side portion A^2 , which may be considered a part of the vehicle-body, said lug 40 having a bolt extension and the part g being a nut which screws onto the bolt and against a perforated reinforcing-block h , which is brazed or otherwise securely fastened on the inner side of the sheet-metal back at a location corresponding to the outer side of the vehicle-body. The said lug and bolt f being horizontal, the seat may be brought to place as it is slid rearwardly to position of support on the front and rear girders B.
- 45. Having thus described my invention, what I claim, and desire to secure by Letters Patent, is—

- 1. The combination with a vehicle-body and a pair of seats having seat-bottoms and rounded backs with forward upright continuations arranged side by side, of a rigid metallic part overlying the edges of said seat-back continuations, and having an angular projection extending from its inner side between said 55 formed continuations, and means for fastening said projection and said upright continuations together.
- 2. The combination with a vehicle-body and a pair of seats having seat-bottoms and rounded backs with forward upright continuations

arranged side by side, of a rigid metallic part overlying the edges of said seat-back continuations, and having projections extending from its inner side between said continuations, and bolts passed through the latter and through 75 said projections and provided with confining-nuts therefor.

3. The combination with a vehicle-body and a pair of seats having seat-bottoms and rounded backs with forward upright continuations arranged side by side, of a rigid metallic part overlying the forward edges of said continuations, having projections extending from its inner side between said continuations, and having at its lower end oppositely-projecting 80 members for engaging the seat-bottom fronts, and fastenings transversely applied through the seat-back continuations, and through the projections intermediate thereof.

4. The combination with a vehicle-body and a pair of seats having seat-bottoms and rounded backs with forward upright continuations arranged side by side, of a rigid metallic part overlying the forward edges of the adjacent continuations of the two seats, and having 90 connection therewith at the inner side of said part, and said part having at its lower end an inwardly-extending projection to overlie a horizontal seat-supporting part of the body, and by means of which to fasten it to such 95 seat-supporting part.

5. The combination with a vehicle-body and a pair of individual seats comprising seat-bottoms and rounded backs with forward upright continuations arranged side by side and slightly 100 separated, of a rigid metallic part overlying the forward edges of the adjacent continuations of the two seats, and having connection therewith inside of said part, and said metallic part having at its lower end oppositely-projecting members for engaging the seat-bottom fronts, and an inward projection or 105 projections to extend under the seat, and by means of which to fasten it to the seat-supporting part of the vehicle-body.

6. The combination with a vehicle-body and a pair of seats having seat-bottoms and rounded backs with forward upright continuations arranged side by side and having at the upper edges of the backs the angle-bars secured 115 thereto, and which as to those continuations of the back which are adjacent each other, are terminated above and to the rear of the front of the seat-bottom, a rigid metallic part overlying the forward edge portions of the adjacent continuations being facewise continuous with the top faces of the merged-together angle-bars of the two seats and having fastenings internally thereof with the seat sides or 120 continuations.

7. The combination with a vehicle-body having a transverse member B which at its top comprises an angle-bar with the upper member thereof horizontal, and the pair of separately-constructed seats having seat-bot- 125 130

- toms and rounded backs with forward upright continuations arranged side by side and resting on said transverse member, of a rigid metallic part overlying the edges of said seat-back continuations having fastening at its inner side connecting it to said adjacent seat parts and having at its bottom an inwardly-extended member resting on the horizontal member of said part B and having vertically-applied fastenings through it and said member.
8. The combination with a vehicle-body and the pair of individual seats having rounded backs and side continuations substantially as described, and said backs having at the upper edges the angle-bars *c c* merged together and terminated as shown, of a rigid metallic part overlying the forward edge portions of the adjacent sides, facewise continuous with the upper faces of the angle-bars of the two adjoining seats, and having at its rear end portion the rabbet 15, the base of which underlaps the angle-bars, and fastenings applied at the inner sides of said rigid metallic part connecting it with the adjacent side portions of the two seats.
9. The combination with a vehicle-body having at opposite sides thereof the parts *f* comprising lug members secured to the body and horizontal bolt extensions, of the pair of seats C C having backs provided with perforations therein located to match in line with said bolt extensions, and the fastening-nuts *g* applied at the forward sides of the seats screw-engaging the bolts.
- 35 10. The combination with a vehicle-body

having at opposite sides thereof the parts *f* comprising lug members secured to the body and horizontal bolt extensions thereof, of the pair of seats C C having backs provided with perforations and the reinforcing perforated blocks *h* in line with said bolt extensions, and the nut *g* screw-engaging said bolts against said blocks at the forward side of the seat-backs.

11. The combination with a vehicle-body having opposite lugs *f f* and the pair of seats C C having backs, supported on the body and arranged to adjoin the side pieces, said lugs and seat-backs being constructed and provided, relatively, the one with horizontal longitudinal-ranging bolts or studs and the other with perforations located in line with and to match with said bolts, and arranged for engagement and disengagement by horizontal rearward and forward sliding movements of the seats on the body.

12. For a vehicle-body and seat-fastening, the rigid metallic part G consisting of the median member 11 having at its inner side the transversely-perforated angularly-extended lugs 12 12 having at its lower end the oppositely-extending members 7 7, and provided with one or more angular and rearwardly-extended members 17.

Signed by me at Springfield, Massachusetts, in presence of two subscribing witnesses.

HINSDALE SMITH.
